(57) **CLAIM**

The ornamental design for a laser pointing device, as shown and described.

DESCRIPTION

FIG. 1 is a perspective view of a first embodiment of a laser pointing device showing our new design;
FIG. 2 is a top plan view thereof;

FIG. 3 is a front elevational view thereof, the rear elevational view being a mirror image thereof;

FIG. 4 is a bottom elevational view thereof;

FIG. 5 is a left side elevational view; and

FIG. 6 is a right side elevational view.

FIG. 7 is a perspective view of a second embodiment of a laser pointing device showing our new design;

FIG. 8 is a top plan view thereof;

FIG. 9 is a front elevational view thereof, the rear elevational view being a mirror image thereof;

FIG. 10 is a bottom elevational view thereof;

FIG. 11 is a left side elevational view; and

FIG. 12 is a right side elevational view.

FIG. 13 is a perspective view of a third embodiment of a laser pointing device showing our new design;

FIG. 14 is a top plan view thereof;

FIG. 15 is a front elevational view thereof, the rear elevational view being a mirror image thereof;

FIG. 16 is a bottom elevational view thereof;

FIG. 17 is a left side elevational view; and

FIG. 18 is a right side elevational view.

FIG. 19 is a perspective view of a fourth embodiment of a laser pointing device showing our new design;

FIG. 20 is a top plan view thereof;

FIG. 21 is a front elevational view thereof, the rear elevational view being a mirror image thereof;

FIG. 22 is a bottom elevational view thereof;

FIG. 23 is a left side elevational view; and,

FIG. 24 is a right side elevational view.
